Term of patent 14 years

(Cl. D91—3)

FIG. 1

FIG. 3

FIG. 2

FIG. 4

Fig. 1 is a front perspective view of a valve body embodying my new design;

Fig. 2 is a bottom plan view;

Fig. 3 is an elevational view of one side; and

Fig. 4 is an elevational view of the opposite side thereof.

The rear of the valve body is like the front except that it is without the arrow, plate and boss.

I claim:

The ornamental design for a valve body, as shown and described.
